CLAIM

The ornamental design for a reader housing, as shown and described.

DESCRIPTION

FIG. 1 is an isometric view of the first embodiment of the reader housing;
FIG. 2 is a front view of the reader housing of FIG. 1;
FIG. 3 is a rear view of the reader housing of FIG. 1;
FIG. 4 is a left side view of the reader housing of FIG. 1;
FIG. 5 is a right side view of the reader housing of FIG. 1;
FIG. 6 is a top view of the reader housing of FIG. 1;
FIG. 7 is a bottom view of the reader housing of FIG. 1;
FIG. 8 is another isometric view of the reader housing of FIG. 1, but shown with different broken line subject matter.
FIG. 9 is a front view of the reader housing of FIG. 8;
FIG. 10 is a rear view of the reader housing of FIG. 8;
FIG. 11 is a left side view of the reader housing of FIG. 8;
FIG. 12 is a right side view of the reader housing of FIG. 8;
FIG. 13 is a top view of the reader housing of FIG. 8;
FIG. 14 is a bottom view of the reader housing of FIG. 8;
FIG. 15 is another isometric view of the reader housing of FIG. 1, but shown with different broken line subject matter.
FIG. 16 is a front view of the reader housing of FIG. 15;
FIG. 17 is a rear view of the reader housing of FIG. 15;
FIG. 18 is a left side view of the reader housing of FIG. 15;
FIG. 19 is a right side view of the reader housing of FIG. 15;
FIG. 20 is a top view of the reader housing of FIG. 15;
FIG. 21 is a bottom view of the reader housing of FIG. 15;
FIG. 22 is another isometric view of the reader housing of FIG. 1, but shown with different broken line subject matter.
FIG. 23 is a front view of the reader housing of FIG. 22;
FIG. 24 is a rear view of the reader housing of FIG. 22;
FIG. 25 is a left side view of the reader housing of FIG. 22;
FIG. 26 is a right side view of the reader housing of FIG. 22;
FIG. 27 is a top view of the reader housing of FIG. 22;
FIG. 28 is a bottom view of the reader housing of FIG. 22;
FIG. 29 is an isometric view of the second embodiment of a reader housing;
FIG. 30 is a front view of the reader housing of FIG. 29;
FIG. 31 is a rear view of the reader housing of FIG. 29;
FIG. 32 is a left side view of the reader housing of FIG. 29;
FIG. 33 is a right side view of the reader housing of FIG. 29;
FIG. 34 is a top view of the reader housing of FIG. 29;
FIG. 35 is a bottom view of the reader housing of FIG. 29;

(Continued)

FIG. 36 is another isometric view of the reader housing of FIG. 29, but shown with different broken line subject matter. FIG. 37 is a front view of the reader housing of FIG. 36; FIG. 38 is a rear view of the reader housing of FIG. 36; FIG. 39 is a left side view of the reader housing of FIG. 36; FIG. 40 is a right side view of the reader housing of FIG. 36; FIG. 41 is a top view of the reader housing of FIG. 36; FIG. 42 is a bottom view of the reader housing of FIG. 36; FIG. 43 is another isometric view of the reader housing of FIG. 29, but shown with different broken line subject matter. FIG. 44 is a front view of the reader housing of FIG. 43; FIG. 45 is a rear view of the reader housing of FIG. 43; FIG. 46 is a left side view of the reader housing of FIG. 43; FIG. 47 is a right side view of the reader housing of FIG. 43; FIG. 48 is a top view of the reader housing of FIG. 43; FIG. 49 is a bottom view of the reader housing of FIG. 43; FIG. 50 is another isometric view of the reader housing of FIG. 29, but shown with different broken line subject matter. FIG. 51 is a front view of the reader housing of FIG. 50; FIG. 52 is a rear view of the reader housing of FIG. 50; FIG. 53 is a left side view of the reader housing of FIG. 50; FIG. 54 is a right side view of the reader housing of FIG. 50; FIG. 55 is a top view of the reader housing of FIG. 50; FIG. 56 is a bottom view of the reader housing of FIG. 50; FIG. 57 is an isometric view of the third embodiment of a reader housing; FIG. 58 is a front view of the reader housing of FIG. 57; FIG. 59 is a rear view of the reader housing of FIG. 57; FIG. 60 is a left side view of the reader housing of FIG. 57; FIG. 61 is a right side view of the reader housing of FIG. 57; FIG. 62 is a top view of the reader housing of FIG. 57; and, FIG. 63 is a bottom view of the reader housing of FIG. 57. The broken lines illustrate portions of the reader housing that form no part of the claimed design.
